UNITED STATES PATENT OFFICE.

WILLIS T. HURST, OF PITTSBURGH, PENNSYLVANIA.

CASTING MECHANISM.

1,115,201.

Specification of Letters Patent. Patented Oct. 27, 1914.

Application filed November 19, 1913. Serial No. 801,818.

To all whom it may concern:

Be it known that I, WILLIS T. HURST, a citizen of the United States, residing at Pittsburgh, in the county of Allegheny and State of Pennsylvania, have invented certain new and useful Improvements in Casting Mechanism, of which the following is a specification.

My invention has for its object to provide a continuous casting mechanism for molten metal for forming it into pigs; discharging the same at an assembling position; cooling the assembled pigs in a receiving vat or receptacle, especially adapted to the purpose; and then removing the pigs in quantities for shipment or storage.

The apparatus is of the same general type in common use, wherein a series of loosely connected molds in the form of an endless conveyer are passed underneath a supplying spout from any suitable vessel containing the molten metal, and are cooled in their passage along the conveyer, with the addition of water-spraying mechanism if desired, the pigs being discharged from the molds in sufficiently cool form to retain their shape.

In the present invention I utilize one or more continuous conveyers of suitable construction, discharging the pigs into a receiving vat where they are cooled by a water spray, the vat being provided with a filtering bottom adapted to allow drainage of the water, and without loss of any of the metal.

One preferred arrangement of the apparatus is illustrated in the accompanying drawings, in which:

Figure 1 represents a general plan view, partly broken away, showing the distributing ladle and trough, a pair of conveyers, the cooling vat, lifting crane, etc. Fig. 2 is a view of the apparatus in side elevation, partly broken away. Fig. 3 is an enlarged sectional detail view of the filtering cooling vat and its parts. Fig. 4 is a transverse sectional view showing the magnetic lifting crane and the surrounding construction with relation to the cooling vat. Figs. 5 and 6 are detail sectional views showing a plurality of the connected molds. Fig. 7 is a sectional detail view showing a modified construction of cooling vat.

The molten metal to be formed into pigs, as molten iron, is brought by a suitable vessel, as ladle 2, upon a buggy traveling on tracks 3, or by other suitable means, into

convenient position for discharging its molten contents into the pouring pot 4, provided with the runner 5, having a discharge terminal 6, leading to the central portion of the molds which travel along on centers *a*, *a*. Said molds, which are of well-known construction, and as indicated in Figs. 5 and 6, are provided with longitudinal receiving recesses 7, and each mold overlaps the next adjacent molds in the manner indicated at 8, whereby to prevent loss of surplus metal, as is well understood.

The molds are connected together by suitable link mechanism which is mounted upon the driving head and supporting tail wheels, 9, 10, forming an endless conveyer, two such complete conveyers being shown in the drawings, operating side by side for increased capacity.

The head or driving sprocket wheels 9 are geared in any suitable manner, as by gearing 11 with a motor 12 of any suitable type, whereby to actuate the mechanism, the series of molds being preferably slightly inclined upwardly toward the discharge points.

At the terminals of the conveying movement, the molds pass around over head wheels 9, the formed pigs falling by gravity upon inclined chutes 13, by which they are discharged over and downwardly into the pig cooling vat 14. Said vat is of considerable size, having surrounding walls 15 of concrete or other suitable material and a bottom 16, preferably sloping toward a centrally arranged sewer outlet 17. Within the walls 15, and above bottom 16, are laid a series of filtering elements in layers as shown, a bottom layer 18 of crushed stone, a next adjacent layer 19 of sand, and a covering uppermost layer 20 of crushed limestone or gravel. The limestone or gravel layer 20 forms the receiving bed for the pigs and is formed in hollow depressed arrangement within the walls 15, providing a receiving bottom for the pigs as they are discharged into the cooling vat from chute 13.

Located conveniently above the vat and disposed so as to discharge downwardly into it, are water spray pipes 21, 21, leading from any suitable source of supply and having proper controlling valves, etc., by which cooling water is sprayed upon the accumulating pigs as they are received in the vat, further cooling them for transportation. The water passing from the surfaces of the pigs and downwardly through the filtering

beds finally passes off through opening 17 to the sewer, any loose particles of metal being arrested and retained in the bed of the vat upon the surface of the uppermost layer 20 of limestone or gravel. An especial advantage of such construction and operation is that any spraying of the pigs in the cars is rendered unnecessary, avoiding objectionable accumulation of water and ice, the pigs being delivered to the cars in dry condition, while also protecting the cars from the burning effect of too hot metal.

In Fig. 7 I show a modified construction of cooling vat in which the walls 15' extend considerably higher above the bottom 16' and above the uppermost layer 20' of limestone or gravel. By this construction I provide a water holding cavity or bath 30 for the pigs of considerable depth, to which water is supplied by a supply pipe 21' in any desired volume for maintaining a body of water within the surrounding walls 15'. The water thus completely or practically covers the accumulating pigs, passing off downwardly to the sewer 17' through the uppermost supporting layer 20', the sand layer 19' and bottom layer 18' and finally to sewer conduit 17'. The object in placing the sand filtering layer below the gravel or sandstone surface layer is to prevent adherence of the sand to the pigs, while at the same time insuring thorough filtering of the water.

For the purpose of removing the pigs, I provide a lifting magnet 22 of well-known construction, suitably connected with any source of current as by conductor 23. The magnet depends from a traveling carriage or trolley 24, mounted upon the supporting frame-work and tracks 25 of a traveling crane, which in turn is mounted by its wheels 26 upon supporting tracks 27, whereby the crane may have any desired or necessary travel. It will be understood that the crane, which is of well-known construction, is provided with suitable controlling mechanism, whereby it may be operated to raise and lower the lifting magnet and to shift the load longitudinally or laterally to discharge 50 into a receiving car 28 at either side of the cooling vat, or elsewhere, as preferred.

The advantages of the invention reside in its facility for direct, economical and rapid treatment of the metal, prompt and efficient cooling; salvage of any surplus or loose metal within the cooling vat, removal of the cooled pigs as they accumulate in the vat, and prevention of any necessity of delivering hot pigs to the car or other transporting vessel. The accumulated pigs in the vat, being closely associated together, are in convenient position for attachment and lifting by the magnetic crane, thereby increasing the capacity and usefulness of the crane in gathering and moving large numbers of

pigs. By means of the universal adjustment of the lifting magnet 22, it will be seen that the pigs may be removed from any portion of the vat as they accumulate, allowing the most recently delivered pigs to remain sufficiently long under the action of the cooling spray to insure their setting.

The pigs in transit may be preliminarily cooled by means of spray pipes 29, as shown in Fig. 1, such spray pipes being located at a suitable distance above the traveling mold. These are of well-known construction, having series of jet openings for delivering water downwardly over the molded pigs.

The apparatus may be built in any desired capacity, the length of the conveyer, the size and form of the molds being within the normal requirements of the installation, and the invention may be otherwise changed or varied by the designing engineer or skilled mechanic, within the scope of the following claims.

What I claim is:—

1. In casting apparatus, the combination with a series of elevated traveling molds adapted to turn over and empty molded pigs at a given point, of a permanently stationary receiving vat for the metal at and below such point provided with an uppermost recessed receiving layer of suitable material, a filtering bottom, and a water outlet, and means for supplying water to said vat and its contents, substantially as set forth.

2. In casting apparatus, the combination with a series of elevated traveling molds adapted to turn over and empty molded pigs at a given point, of a permanently stationary receiving vat for the metal at and below such point provided with an uppermost recessed receiving layer of suitable material, a filtering bottom, and a water outlet, means for supplying water to said vat and its contents, and means for removing molded pigs upwardly from the vat, substantially as set forth.

3. In casting apparatus, the combination with a series of traveling molds adapted to turn over and empty molded pigs at a given point, of a receiving vat for the metal at such point provided with a filtering bottom, means for supplying water to the vat for cooling the cast metal therein, and a superimposed magnetic lift for removing the cast metal from the mold, substantially as set forth.

4. In casting apparatus, the combination with a series of traveling molds in the form of an endless conveyer, means for supplying molten metal to the molds, and a terminal receiving chute adapted to receive the molded metal as the molds discharge it; of a cooling vat having a concaved filtering bottom of suitable material adapted to receive

the metal from the chute, a sewer outlet below the filtering bottom, and means for supplying water to the vat and the cast metal therein, substantially as set forth.

- 5 5. In casting apparatus, the combination with a series of traveling molds in the form of an endless conveyer operable to reverse and empty around terminal supporting wheels, means for supplying molten metal 10 to the molds, and a terminal receiving chute for the discharged molded units; of a cooling vat having a concaved filtering bottom of suitable material, a sewer outlet below the filtering bottom, means for supplying water 15 to the vat and the cast metal therein, and a superimposed magnetic lift for extracting portions of the cast metal from the vat, substantially as set forth.
6. In casting apparatus, the combination 20 with a series of traveling forming and discharging molds, of a receiving vat for the molded metal consisting of a supporting bottom and surrounding walls, a sewer outlet below the bottom, a plurality of intervening 25 layers of suitable supporting and filtering material, and a water supply device adapted to discharge water to the vat and its contents, substantially as set forth.
7. In casting apparatus, the combination

with a series of traveling forming and discharging molds, of a receiving vat for the molded metal consisting of a supporting bottom and surrounding walls, a sewer outlet below the bottom, a plurality of intervening 30 layers of suitable supporting and filtering material embodying a layer of sand, and means for supplying water to the vat and the cast metal contained therein, substantially as set forth.

8. In casting apparatus, the combination 35 with a series of traveling forming and discharging molds, of a receiving vat for the molded metal consisting of a supporting bottom and surrounding walls, a sewer outlet below the bottom, a plurality of intervening 40 layers of suitable supporting and filtering material embodying a layer of sand, means for supplying water to the vat and the cast metal contained therein, and means for removing the cooled metal from the vat, substantially as set forth.

In testimony whereof I hereunto affix my signature in the presence of two witnesses.

WILLIS T. HURST.
